UNITED STATES PATENT OFFICE.

THOMAS DINSEN AND JOHN J. KRICKER, OF NEW YORK, N. Y.

DISPLAY STAND.

1,426,156.

Specification of Letters Patent. Patented Aug. 15, 1922.

Application filed November 23, 1920, Serial No. 426,097.

To all whom it may concern:

Be it known that we, THOMAS DINSEN, a citizen of the United States, residing in the city, county, and State of New York, and 5 JOHN J. KRICKER, a citizen of the United States, residing in the city, county, and State of New York, have invented certain new and useful Improvements in Display Stands, of which the following is a specification.

This invention relates to a display stand for electric lamps and has for its object to provide a device of this character possessing the various new and novel features 15 described in the following specification, having reference to the accompanying drawings, in which—

Figure 1 is a front elevation of one form of display stand embodying the invention;

20 Figure 2 is a side view of Figure 1;

Figure 3 is a plan view of part of the mechanism of Figures 1 and 2;

Figure 4 is a view showing part of the mechanism of Figure 3 in longitudinal section;

Figure 5 is a diagram showing the circuit connections employed, and

Figure 6 is a detail view showing a member of the mechanism illustrated in Figures 30 3 and 4.

Similar characters of reference designate similar parts in each of the several views.

The display stand illustrated in Figures 1 and 2 comprises a vertical frame A 35 mounted on a table B. The frame A comprises a pair of uprights *a*, *a* joined by a pair of horizontal members *c*, *c*, but it is to be understood that this is merely illustrative of one form of embodiment of the 40 invention and that any desired form and shape of display frame may be employed. The members of the frame are preferably hollow to receive the wires of electric lamps which are mounted in sockets placed on 45 the frame at suitable points, as illustrated, and numerals are conspicuously placed on the frame to designate the various lamps, as indicated in the drawing. It will be understood that all types and kinds of electric lamps may be placed into the sockets of the stand and that these lamps may be changed when desired by the exhibitor.

On the table B are provided control handles 20 and 21, each of which handles is arranged to govern the circuit of the various lamps, so that by proper manipulation of

these handles it is possible to bring about the lighting of any desired lamp. For this purpose the handle 20 is affixed to a shaft 22 (Figure 4), which shaft extends through the casing 23 and carries a contact arm 24. Similarly, control handle 21 is affixed to a sleeve 25 which is free to rotate on shaft 22 and carries a contact arm 26. The above contact arms are arranged to cooperate with a number of contacts 27 (see Figure 5) and with segmental contact rings 28 and 29, the longer contact arm being arranged to connect the outer contact ring with the particular contact 27 with which it is in engagement, and the shorter contact arm being arranged to provide similar connection between the said contacts and the inner contact ring 29. Contacts 27 are insulated from each other and from the rings 28 and 29 and each contact is connected to one of the lamps displayed on the stand. In the diagram, however, only a few of these contacts have been shown so connected in order to avoid confusion. The contact rings are connected in parallel with each other to one terminal of a source of current 30, a meter 31 being interposed in this connection, and one side of each of the lamps is connected to the other terminal of the 80 source of current 30. In the illustrated positions of the control handles 20 and 21, the contact arm 26 completes the circuit of the lamp 9, so that current flows from one terminal of the source of current through 90 meter 31, contact ring 29, contact member 26 and the contact with which the same is in engagement, and lamp 9, to the other terminal of the source 30. This lamp is thus caused to glow. Control handle 20 is in such position that contact arm 24 completes the circuit of the incandescent lamp 7, so that this lamp is caused to glow simultaneously with lamp 9. A comparison between lamps 7 and 9, or any other desired pair 100 of lamps on the stand, may thus be had and a customer may thus make selection of the lamp or lamps which will meet his purpose.

To facilitate the selection of the lamps, 105 the control handles 20 and 21 are provided with pointers 32 and 33, respectively, which cooperate with a scale on the face of the casing 23, which scale, in the illustrated embodiment, consists of the numbers 1 to 17, 110 inclusive, which are so spaced from each other that when the pointer of either han-

dle is brought opposite any number, the corresponding lamp will be caused to glow. The operator may, therefore, light any lamp he desires by turning either handle until 5 the pointer thereof coincides with the numeral corresponding to the lamp.

To give the operator information as to the cost of the lamp which is illuminated, the voltage thereof, or any other desired 10 features, the invention provides in the face of the casing 23 a pair of slots 34 and 35 with which a pair of segmental discs 36 and 37, affixed respectively to sleeve 25 and shaft 22, are arranged to cooperate. One of these 15 discs, 36, is illustrated in Figure 6. It is made preferably of ground glass or other transparent material and is provided adjacent its rim with a scale 38 containing as many divisions as there are lamps on the stand, 20 each division containing an inscription or legend pertaining to the lamp to which it corresponds. In the drawing, the numbers appearing in slot 34 show that lamp 9 consumes 15 watts and sells for forty cents. 25 The numbers appearing in slot 35 indicate that lamp 7 consumes 60 watts and sells for forty-five cents. The customer is thus able to ascertain the wattage and cost of any 30 of the lamps on the display stand. To enhance the clearness of the indications in slots 34 and 35, electric lamps 38 are mounted behind the segments 36 and 37.

The dial of meter 31 is calibrated preferably in terms of cost per hour for the 35 electrical energy which is consumed by the lighted lamp. Although in the illustrated positions of the control handles the indication of the meter gives the combined cost per hour of lamps 7 and 9, it will be understood that the cost of operating either alone 40 may be obtained by turning the one handle beyond the scale so that the corresponding contact arm is brought beyond the ends of the contact rings and only the desired one 45 of the lamps is lighted.

It will thus be seen that the stand of this invention serves not only to display the lamps in an attractive manner, but is provided with devices whereby the customer 50 himself, by the mere turn of a handle, may light any desired lamp and ascertain its brilliancy of illumination, its cost, its wattage, its current consumption or operating cost and any other features with which the 55 exhibitor desires to acquaint him. He may, moreover, light any two of the lamps simultaneously and thus compare them in actual operation.

Although only one specific form of embodiment of the invention is shown and described herein, it is to be understood that many changes and modifications may be made therein, it being intended to cover the invention broadly in whatever form its 60 principle may be embodied.

What is claimed is:

1. In combination, a fixed display frame, members thereon for receiving devices to be exhibited, a pair of terminals on said frame for connection to a source of electric potential, and manually operable means whereby any one of said members without changing its position may be connected to said pair of terminals independently of the other members. 75

2. In combination, a display frame, members thereon for receiving electric lamps, and selective switching means whereby any desired pair of said lamps may be connected with a source of electric current. 80

3. In combination, a display frame, members mounted thereon for receiving electric devices to be exhibited, a pair of terminals thereon for being connected to a source of electric potential, a series of contacts corresponding, respectively, to said members, electric circuit connections for connecting said contacts to said members, a manually operable member movable relatively to said first-mentioned members for cooperating 90 with said contacts, connections between said manually operable member and one of said terminals and between said first-mentioned members and the other of said terminals, and an electric indicating instrument interposed in said connections. 95

4. In combination, a display stand, members thereon for receiving devices to be exhibited, electric circuits for said members, a controlling device for governing said circuits, a scale adapted to receive characters thereon corresponding to said members and means operatively connected to said controlling device for co-operating with said scale. 100

5. In combination, a display stand, members thereon for receiving devices to be exhibited, electric circuits for said members, a single source of current for said circuits and a plurality of controlling devices independent of each other for selectively 105 governing said electric circuits whereby the circuits of any two of said members may be closed simultaneously. 110

6. In combination, a display stand for electric devices, electric circuits for said devices, a controller for selectively governing said circuits, a member adapted to receive legends thereon corresponding to said devices and means governed by said controller for exposing only such part of said legends 115 as corresponds to the device whose circuit is selectively operated by said controller. 120

7. A display device comprising members for receiving devices to be displayed, said display device being adapted to receive reference characters for identifying the devices displayed thereon, electrical circuits connected to said members, means for governing said electrical circuits, and indicating means operably connected with said govern- 125 130

ing means, said indicating means being provided with reference characters corresponding to the reference characters of the display device.

5 8. In combination, a display frame, electrical display members provided on said frame, contacts electrically connected to said electrical display members, a member for co-operating with said contacts to selectively govern said display members, a pointer governed by said member, a scale with which said pointer is adapted to operate, and means whereby the divisions of said scale may be identified with reference to 10 the display members displayed on said frame.

9. In combination, a display frame, electrical devices mounted thereon, circuits for said devices, means for selectively governing said circuits, a scale for identifying said 20 devices, a member connected with said governing means and co-operating with said scale whereby said means may be caused to govern the circuit of such electrical device as corresponds to the division of said scale 25 with which said member is in registry.

10. In combination, a display frame, electrical devices mounted thereon, circuits for said devices, means for selectively governing said circuits, a scale for identifying said 30 devices, a member connected with said governing means and co-operating with said scale whereby said means may be caused to govern the circuit of such electrical device as corresponds to the division of said 35 scale with which said member is in registry, and means responsive to said member for

selectively displaying legends corresponding to said electrical devices.

11. In combination, a display stand, a plurality of electrical devices mounted thereon in fixed position, a plurality of contact members selectively connected to said devices, terminal members adapted to be connected to a source of current and a plurality of contact devices for co-operating with said 40 contact members to selectively connect any one or any two thereof with said terminal members.

12. In combination, a display stand, a plurality of electrical devices mounted thereon, a plurality of contact members selectively connected to said members, a plurality of contact devices for co-operating with said members to selectively connect one or any two thereof with a source of current, a scale 50 having legends corresponding to said electrical display devices, and indicating members provided on said contact devices for co-operating with said scale.

13. In combination, a display stand, for 60 a plurality of electric articles, means for selectively governing said articles, a translucent member provided on said means, means for exposing only such part of said translucent member as relates to the particular article being governed by said governing means, and means for illuminating said part of said member.

In testimony whereof we have affixed our signatures to this specification.

THOMAS DINSEN.
JOHN J. KRICKER.
